Primary Examiner—Carmen H. Vales-Lado*Assistant Examiner*—Jeffrey Asch*Attorney, Agent, or Firm*—Killworth, Gottman, Hagan & Schaeff[57] **CLAIM**

The ornamental design for a display stand for writing instruments, as shown and described.

DESCRIPTION

FIG. 1 is a perspective view of display stand for writing instruments showing our new design;

FIG. 2 is a front elevational view;

FIG. 3 is a top plan view; and,

FIG. 4 is a left side elevational view, the right side being a mirror image thereof.

The broken line showings in FIGS. 1 and 3 are for illustrative purposes only.

FIG-3

FIG-4
